(57) **CLAIM**

The ornamental design for a hitch lock packaging, as shown and described.

DESCRIPTION

FIG. 1 is a perspective view of the first embodiment of the hitch lock packaging and container for the present invention; FIG. 2 is a side view of the design shown in FIG. 1; FIG. 3 is a front view of the design shown in FIG. 1; FIG. 4 is a side view of the design shown in FIG. 1; FIG. 5 is a back view of the design shown in FIG. 1; FIG. 6 is a top view of the design shown in FIG. 1; FIG. 7 is a bottom view of the design shown in FIG. 1; FIG. 8 is a perspective view of the second embodiment of the hitch lock packaging and container of the present invention;

FIG. 9 is a side view of the design shown in FIG. 8; FIG. 10 is a front view of the design shown in FIG. 8; FIG. 11 is a side view of the design shown in FIG. 8; FIG. 12 is a back view of the design shown in FIG. 8; FIG. 13 is a top view of the design shown in FIG. 8; and, FIG. 14 is a bottom view of the design shown in FIG. 8.

The portions of the Figures shown in phantom lines are not part of the claimed design but are for illustration only. The broken lines, which define the bounds of the claimed design, form no part thereof. The broken lines environmental are for illustrative purpose only and form no part of the claimed design.
